(57) **CLAIM**

The ornamental design for a metatarsal guard, as shown and described.

DESCRIPTION

FIG. 1 is a perspective view of a metatarsal guard showing the new design;

FIG. 2 is a top view of the metatarsal guard of FIG. 1;

FIG. 3 is a bottom view of the metatarsal guard of FIG. 1;

FIG. 4 is a right view of the metatarsal guard of FIG. 1;

FIG. 5 is a left view of the metatarsal guard of FIG. 1;

FIG. 6 is a rear view of the metatarsal guard of FIG. 1; and,

FIG. 7 is a front view of the metatarsal guard of FIG. 1.

The broken lines depict portions of the external metatarsal guard that form no part of the claimed design.

1 Claim, 4 Drawing Sheets
